UNITED STATES PATENT OFFICE

90,495

DESIGN FOR A LOUNGING CHAIR

Vernon A. McChesney, Buffalo, and Fred A. Milnes, Kenmore, N. Y., assignors to Aluminum Company of America, of Pittsburgh, Pa., a Corporation of Pennsylvania

Application May 3, 1933. Serial No. 47,987

Term of patent 3½ years

To all whom it may concern:

Be it known that we, VERNON A. MCCHESENEY and FRED A. MILNES, citizens of the United States, residing, respectively, at Buffalo and Kenmore, in the county of Erie and State of New York, have invented a new, original, and ornamental Design for a Lounging Chair of which the following is a specification, reference being had to the accompanying drawing, forming a part thereof.

The figure shown is a perspective view of a lounging chair embodying our new design.

We claim:

The ornamental design for a lounging chair, as shown.

VERNON A. MCCHESENEY.
FRED A. MILNES.
